LOG BARKER AND CLEANER

Ernest C. Shaw, Milwaukee, and William G. Hagermaier, West Allis, Wis., assignors to Allis-Chalmers Manufacturing Company, Milwaukee, Wis., a corporation of Delaware

Application August 3, 1940, Serial No. 350,506

6 Claims. (Cl. 144—208)

This invention relates to improvements in devices for removing bark from logs and for cleaning logs and more particularly to so-called log barkers and log cleaners of the type employing a combination of a high pressure hydraulic jet with controlled abrasion means and scoring means for the continuous treatment of logs.

Bark and other material must be removed from logs and even peeled logs must be cleaned after storage and before use to supply wood fiber for making paper or other cellulose products. Logs to be barked or cleaned are not uniform in any respect but vary widely particularly as to species of wood, size, the presence of knots and stubs and of pockets with gnarled wood, pitch or gritty substances. In the handling of logs, metallic objects are frequently placed in the wood or objects such as stones become embedded in the wood and the storage of logs particularly facilitates the growth of fungi, all of which objects and growths must be removed before the wood fiber can be used to produce first quality paper or other material. Logs may be received shortly after cutting and without storage and repeated handling or may be received only after extended storage and considerable handling which changes the condition of the bark and the wood from its original condition. It is of course desirable that a machine be provided which will operate on any kind and size of logs, within practical limits, and without adjustment for the kind or size of logs to be handled. All bark and other material should be completely removed from logs, without, however, removing useful wood fiber, thereby exposing all portions of the wood for the discovery and removal of materials of any nature which may have a deleterious effect on the quality of the fiber obtained and for the discovery and removal of foreign material likely to cause difficulty in fiber separation. Such complete bark removal must be accomplished without regard to the condition of the bark or wood of the logs to be treated. A commercially successful machine must be continuous in operation and free from the necessity for adjustment by the unskilled labor usually employed to operate such machines. Logs must be so handled by the machine as to avoid splitting and splintering, particularly to avoid the so-called "brooming" of the log ends, and the machine must remove all unsound material even from deep checks resulting from lengthy storing of the logs. Tests have shown that all of the required conditions are fulfilled only if both a high velocity water jet is employed to exercise a wedging impact action

between the bark and the wood and if such jet action is supplemented by a controlled abrasive means employed to remove material not removable by the water jet. The jet action is facilitated if means are provided to produce cuts or apertures through the bark as points at which the jet may act between the bark and the wood.

It is therefore an object of the present invention to provide a machine for removing bark and foreign material from logs without the removal of useful wood fiber and without changing either the physical or chemical condition of the wood fiber.

Another object of the invention is to provide a log barker for the continuous barking of logs varying in size within specified limits and operating on such varying sizes without any adjustment whatever of the barker.

Another object of the invention is to provide a log barker and cleaner which will effectively remove bark and otherwise clean logs down to sound wood fiber without regard to the kind or condition of the logs supplied.

Another object of the invention is to provide a log barker and cleaner in which the action of a fluid jet between the bark and wood is supplemented by brushing after the jet action takes place.

Another object of the invention is to provide a log barker employing a combination of high pressure hydraulic jets, cutting or scoring means for facilitating the action of the jets and abrasive means for removing all material from the logs excepting wood useful for fiber production.

Objects and advantages other than those above set forth will be apparent from the following description when read in connection with the accompanying drawings, in which:

Fig. 1 is a top view of a log barker and cleaner according to the present invention, with the cover and fluid jets supported thereon removed, to illustrate the arrangement of the means for feeding the logs into the barker, for rotating the logs in passage through the barker and for the abrasive removal of bark not removed by the action of the jet;

Fig. 2 is a side view, partially in section and partially in elevation, of the structure shown in Fig. 1;

Fig. 3 is a vertical outside end view to illustrate generally the structure of the log barker or cleaner and particularly the discharge end of the machine;

Fig. 4 is a vertical cross sectional view taken on the plane IV—IV of Fig. 1 to illustrate the means

for directing the hydraulic jets on the logs and the manner in which the fluid jets and the abrasive means cooperate for removing the bark from the logs;

Fig. 5 is an end view of one of the several fluted rolls forming the means for rotating the logs during their passage through the machine;

Fig. 6 is a side elevation view illustrating the threaded surface of an alternative form of roll for cooperating with a fluted roll in rotating the logs in their passage through the machine and to assist in passing the logs through the machine;

Fig. 7 is an end view of the threaded roll shown in Fig. 6;

Fig. 8 is a top view of a modified construction of log barker and cleaner of the present invention with the upper portion thereof removed to illustrate a modified means for rotating the logs in their passage through the machine and for producing a cutting or scoring of the bark together with modified means for abrasive removal of portions of the bark;

Fig. 9 is a side view of the machine partially illustrated in Fig. 8, and is partially in section and partially in elevation, to show particularly the means for feeding the logs into the machine and for subjecting the logs to a fluid jet;

Fig. 10 is a partial sectional view taken on the plane of the line X—X of Fig. 9 to illustrate a modified form of mounting and operation of a means for an abrasive bark removal means; and

Fig. 11 is a view taken on the plane of the broken line XI—XI of Fig. 9 to illustrate the structure and the arrangement of means for feeding the logs into the machine.

Referring more particularly to the drawings by characters of reference, the reference numeral 16 indicates a base frame shown as being constructed of structural steel longitudinal and cross members and forming the support for all of the remainder of the machine. A plurality of bearings are mounted on the base frame 16 and provide supports for two sets of side rolls and a center roll, the sets of side rolls each including end rolls 17, 18 and an idler roll 19 while the center roll 21 is made as a unit. The rolls are all shown in Fig. 1 as being fluted as is shown in section in Fig. 5. The end portions 17 and 18 of the side rolls and the ends of the center rolls 21 are each provided with sprocket wheels as shown at 22, 23 and 24 and idler sprocket wheels 26, 27 are mounted adjacent the sprocket wheels on the ends of the rolls.

The two sets of side rolls and the center rolls are enclosed between side walls 31 and 32 mounted on the base frame 16 and the gap between the inner ends of the end portions 17 and 18 of the side rolls and the idler rolls 19 are bridged by plates as at 33 and 34 extending from the side wall inwardly toward the center roll. The rolls and bridging plates form a double trough extending lengthwise of the machine to receive logs as indicated at 36 and 37 and the two troughs of the machine are substantially separated from each other by a central longitudinal partition 38. The ends of both sides of the roll enclosure or casing are partially closed by splash plates 41 and 42 which are pivotally mounted as at 43 and which are each provided with an arm 44 externally of the casing and provided with an adjustable weight 45 for biasing the plates 41 and 42 toward a vertical position dependent on the size of the logs then passing through the machine and on

which the bottom edges of the plates rest. The side walls 31 and 32 are each provided with a plurality of manholes provided with hinged covers as indicated at 46 to provide access to the interior 5 of the machine at several points along both sides for inspection, and for clearing any jams which may occur within the machine.

A multi-speed motor 51 for controlling the speed of the rolls and the rotation of the logs, 10 is mounted on the base 16 and is provided with a sprocket wheel 52 to receive a chain 53 passing over the other sprocket wheels above mentioned and over an idler sprocket wheel 54 mounted on a base cross member for sliding upon adjustment of 15 a screw 55 to maintain the proper tension on the sprocket chain 53. The motor 51 thus drives all of the rolls and, if the sprocket wheels on the rolls are all of the same size, drives all of the rolls at the same speed. A set of driven sprocket wheels 20 and idlers similar to that above described is mounted on the other ends of the rolls as indicated by the driven sprocket wheel 56 and the idler 57 and is likewise connected by a chain. Power is thus transmitted through the unitary 25 center roll 21 with its sprocket wheels to drive the other chain and the end rolls of the sets of side rolls. The rolls rotate the logs in their passage through the machine and if the rolls are operated at different speeds, exert a shearing strain 30 on the bark which tends to break the bark free from the wood.

The space between the end portions 17 of the side rolls and the idler roll 19 and between the idler roll 19 and the end portions 18 of the side 35 rolls is occupied by rotating brushes 61, 62, 63 and 64 severally mounted on the shafts of motors 66, 67, 68 and 69. The motors are each mounted on a pivot as at 71 and are biased to tilt the brushes upwardly due to the action of a 40 spring 72 compressed between an arm 73 on the motor and a nut 74 on a screw 75 pivotally mounted on the machine base 16. The springs 72 force the brushes 61, 62, 63 and 64 upwardly against logs passing through the machine and rotated in 45 their passage through the machine by the rolls. The brushes 61, etc., are therefore brought in brushing contact with all portions of the logs in a helical path as the logs pass through the machine, due to their combined longitudinal and 50 rotational movement. Brushing the logs is particularly important when logs such as spruce are used in which a thin tough layer of bast fiber is present between the bark and the wood and which is very adherent to the wood.

Logs are fed into troughs 78 and 79 extending from one end of the machine and provided with chains 81 and 82 passing over and driven by the sprockets as indicated at 83 and keyed on the shafts 84 and 85 extending exteriorly of the machine through adjustable bearings 86 and 87. The sprocket chain shafts are severally driven through variable speed transmissions 88 and 89 driven by electric motors 90 and 91. The feed chains are provided with a plurality of lugs indicated at 92 and spaced along the chains a distance determined by the average length of the logs being treated. The lugs 92 provide for positively feeding the logs into the machine and on the rolls which, when only fluted rolls are used, rotate but 70 do not feed the logs in a forward direction. Such forward movement is then provided by the end to end abutment of the logs and is therefore determined by the length of the logs and the rate at which the logs are supplied. The speed of log 75 movement through the machine is accordingly

controlled by the rate of feed which may be increased or retarded dependent on the difficulty or the ease with which the bark is removed.

As the logs pass through the machine with every point on the log surface moving in a helical path due to the forward action of the chains 81 and 82 and the rotating action of the sets of side rolls cooperating with the center roll, the logs are subjected to a series of jets of high pressure water. Water is supplied by a suitable pump (not shown) through a supply line 86 to manifolds 87 and 88 under the control of valves 99 and 100. Manifolds 87 and 88 are suitably supported above the center portions of each log passageway over the rolls and are each provided with a plurality of nozzles as at 102, 103 and 104. The nozzles are especially shaped to produce flat chisel-like jets which are so directed as to strike the logs substantially on top between a line determined by a vertical plane through the average size log and a plane from the nozzle. The jets find any break in the bark of each log and produce a wedging action between the bark and the wood to remove the bark. The jets also hold the logs down on the rolls and prevent the logs from rising at one end due to pressure exerted unequally on the ends of any of the logs by the feed chain.

In operation of the structure above described, logs are placed on feed chains 81, 82 which convey the logs to the troughs formed by the side rolls 17, 18 and 19 and the center roll 21. The logs are rotated by cooperation of the rollers and are held down on the rolls by the action of the jets from the nozzles 102, 103 and 104. The rate and the manner in which the logs pass through the machine are controlled by varying the rate of feed dependent on the condition of the bark and the species of wood from which the bark is to be removed. As the logs pass through the machine in a path combined of the forward movement of the chain and rotation of the rolls, the jets find all breaks in the bark and strip the bark from the wood, the bark falling through the space between the rolls and through the base frame. Particles of bark and any covering of bast fiber not removed by the jet action are removed by the action of rotating brushes 61, 62, 63 and 64 which also remove dirt of various kinds from the outside surface of the logs. It will be observed that one jet is arranged ahead of the brushes, one jet is arranged between the brushes and another jet is arranged back of the brushes in the direction of movement of the logs through the machine, thus providing jet action at the most effective locations.

In the modified structure shown in Figs. 8, 9, 10 and 11, only a single passage for logs is provided rather than the double passage as above described. In the present modification, the base frame is again composed of longitudinal members 111 and cross members 112, preferably of structural steel shapes, to provide support for a plurality of bearings 113 which support a plurality of rolls. One of the rolls is provided with a fluted surface as shown in Fig. 5 and is divided into roll portions 116 and 117 having the adjacent ends spaced from each other and the roll 118 is formed integral and has a surface provided with a buttress thread of relatively low pitch cut into the roll as shown in Figs. 6 and 7. Rolls 116, 117, and 118 are enclosed within side walls 121 and 122 and the space between the adjacent ends of the roll portions 116 and 117 is substantially bridged by a plate 123 extending from its point

of attachment with the side wall 122 toward roll 118, thus forming a trough-like passage for logs, with the rolls and the bridging plate forming the bottom thereof. The roll portions 116 and 117 are provided at the outer ends thereof with sprocket wheels 125 and 126 respectively, and roll 118 is provided at one end with a sprocket wheel 127. A chain 128 passes over sprocket wheel 125 and a sprocket wheel 129 mounted on a shaft 130 extending alongside the base. Shaft 130 is driven by a motor 131 through sprocket wheels 132 and 133 and a chain 134. Another sprocket wheel 136 on shaft 130 is connected by way of a chain 137 with sprocket wheel 126. The rolls 15 cooperate in rotating the logs and the thread on roll 118 cuts into the bark and moves the logs forward while they are being rotated.

A manifold 141 is mounted on a top plate 142 of the machine and is provided with a plurality 20 of nozzles 143 extending through the top plate to project jets of high pressure water from a suitable source on the logs being moved through the machine by the rolls. The nozzles are of a particular kind and are arranged as previously 25 described except that the nozzles are grouped relatively closely together rather than spaced over the entire length of the logs as shown in Figs. 1 and 2. Spray from the impact of the jets on the 30 exterior of the machine is substantially prevented from reaching the 35 edges of such plate in contact with the logs passing through the machine.

The bridge plate 123 terminates short of the periphery of roll 118 to provide a space through which a rotatable brush 148 extends into contact 40 with the logs on the roll. The brush is mounted on the end of a lever 149 pivotally mounted at 150 and having the other end thereof connected by springs 151 with the base frame to press the brush upwardly against the log. The brush is 45 driven by a hydraulic impulse wheel 152 mounted on the lever 149 bearing the brush and supplied with water by way of a nozzle 153 which is connected with the high pressure source. The use 50 of the impulse wheel for driving the brush rather than an electric motor as shown in Fig. 4, avoids the use of special electric motors in a location subject to both splashing and the flow of bark removed from the log.

Logs are positively fed into the machine by the 55 cooperating action of an upper and lower feed chain. A motor 156 is mounted on the top plate 142 of the machine and is connected to a speed changing device 157 through belt drive 158 for changing the speed at which power from the 60 motor is transmitted by way of another belt drive 159 through a gear reducer to a sprocket wheel 161. Sprocket wheel 161 is connected by a chain with sprocket wheel 162 mounted on a shaft 163 in the upper portion of the machine 65 and provided with a sprocket wheel 164 engaging an endless multistrand chain 166. The chain 166 is of the known log conveying type with lugs or dogs and passes over a sprocket wheel 167 supported on a suitable frame which is suspended from a rod 168. Rod 168 extends through the machine top plate 142 and is pivotally connected with a lever 169 which is pivotally mounted at 70 170 and provided with a weight 171 adjustable along the lever from its free end. The position 75 of the log driving chain 166 is therefore variable

dependent on the size of the logs which the chain must engage. A plurality of shafts 176 and 177 are mounted on the machine frame and are provided with sprocket wheels 178 and 179 respectively to receive a log conveying chain 181 extending into the bottom of a trough 182 forming the log inlet of the machine. The lower feed chain 181 is driven by a sprocket wheel 183 connected in the usual manner by a chain 184 with the drive shaft 163 for the upper feed chain 166 and the two chains cooperate in positive feeding of the logs onto the roll.

It will be apparent that the present invention provides a log barking and cleaning machine in which a plurality of rolls form a moving bed for receiving and rotating the logs. Such rolls may be either fluted or provided with a threaded surface and may operate at the same or different speeds. If both of two cooperating rolls are fluted and operate at the same speed, logs fed on the rolls are merely rotated while if two fluted rolls operate at different speeds, a shearing action is obtained which tends to separate the bark from the wood. When two cooperating fluted rolls are used, some means must be provided to secure forward movement of the logs over the rolls. However, use of one threaded roll cooperating with a fluted roll or with another threaded roll at different speeds produces both rotating and forward movement of the logs and also provides means for cutting or at least scoring the bark. If two threaded rolls are operated at different speeds, a shearing action is produced on the bark in addition to the scoring action. A plurality of nozzles are shaped to provide relatively small jets of water which produce a wedging and impact action between the bark and the wood and also serve to hold the logs closely on the rolls to aid the rolls in their rotation or combined rotational and forward movement of the logs. Use of a rotating brush between and after the jet action aids in removing surface matter which is not affected by the pressure jets. Due to the helical movement of the surfaces of the logs through the machine, all portions of each log are brushed at least once in the process. It will be seen that a specially simple and rugged machine has been produced which is useful indoors or out of doors regardless of climatic conditions and which greatly improves the conditions of work in operating such machines as compared with the machines now in use for a similar purpose. The prior limitations as to kind and size of logs which may be treated by a machine are removed and limitations as to the skill of the labor attending the machines are entirely eliminated.

Although but a few embodiments of the present invention have been illustrated and described, it will be apparent to those skilled in the art that various changes and modifications may be made therein within the scope of the claims.

It is claimed and desired to secure by Letters Patent:

1. In a machine for removing bark from logs passing therethrough, a plurality of rolls for receiving and rotating the logs, one of said rolls having a fluted surface and another of said rolls being formed with a threaded surface, said rolls cooperating to cause rotation of the logs and to cause longitudinal movement of the logs relative to said rolls, means for driving said rolls, a nozzle for directing a jet of fluid on the logs, a rotat-

able brush mounted between said nozzle and the discharge end of the machine and for movement into contact with the logs, and means for driving said brush.

- 5 2. In a machine for removing bark from logs passing therethrough, a plurality of rolls for receiving and rotating the logs, one of said rolls having a fluted surface and another of said rolls being formed with a threaded surface, said rolls cooperating to cause rotation of the logs and to cause longitudinal movement of the logs relative to said rolls, means for driving said rolls, said roll drive means rotating said threaded roll at a higher speed than the speed of rotation of said fluted roll, a nozzle for directing a jet of fluid on the logs, a rotatable brush mounted between said nozzle and the discharge end of the machine and for movement into contact with the logs, and means for driving said brush.
- 10 15 3. In a machine for removing bark from logs passed therethrough, a plurality of rolls for receiving and rotating the logs, means for driving said rolls, a nozzle for directing a jet of high pressure fluid on the logs, one of said rolls being divided into several axially spaced portions between said nozzle and the discharge end of the machine, a rotatable brush mounted in the space between said roll portions and movable into contact with the logs, and means for rotating said brush.
- 20 25 4. In a machine for removing bark from logs passed therethrough, a plurality of rolls for receiving and rotating the logs, means for driving said rolls, a plurality of spaced nozzles directing jets of high pressure fluid on different portions of the logs, one of said rolls being divided into several axially spaced portions between said nozzles, rotatable brushes mounted in the spaces between said roll portions and movable into contact with the logs, and means for rotating said brushes.
- 25 30 5. In a machine for removing bark from logs passed therethrough, a plurality of rolls for receiving and rotating the logs, one of said rolls being divided into a plurality of axially spaced portions, means for driving said rolls, a plurality of nozzles severally spaced axially of the spaces between said roll portions to direct jets of high pressure fluid toward said rolls, a plurality of brushes severally arranged in the spaces between said roll portions and movable into contact with the logs, and separate means for rotating each said brush.
- 35 40 6. In a machine for removing bark from logs passed therethrough, a plurality of rolls for receiving and rotating the logs, one of said rolls being divided into a plurality of axially spaced portions, means for driving said rolls, a casing along the sides and over the top of said rolls, splash plates pivotally mounted in said casing for substantially closing the ends thereof, a plurality of nozzles for directing jets of high pressure fluid, said nozzles extending severally through the top of said casing on each side axially of the spaces between said roll portions, a plurality of brushes severally arranged in the spaces between said roll portions and movable into contact with the logs during passage thereof through the machine, means for severally rotating said brushes, a chain for feeding the logs on said rolls, and means for driving said chain.
- 45 50 55 60 65 70
